UNITED STATES PATENT OFFICE.

SYDNEY I. PRESCOTT, OF BROOKLYN, NEW YORK.

CARBURETER.

Specification of Letters Patent. Patented June 15, 1915.

1,143,227.

Continuation of application Serial No. 870,746, filed November 7, 1914. This application filed December 1, 1914. Serial No. 874,972.

To all whom it may concern:

Be it known that I, SYDNEY I. PRESCOTT, a citizen of the United States, residing at Brooklyn, county of Kings, and State of New York, have invented a new and useful Improvement in Carbureters, of which the following is a specification.

This invention relates to an improvement in carbureters, and this application is a continuation of my earlier application Serial No. 870746, filed November 7, 1914.

Most carbureters heretofore known have included in one form or another a small air intake or Venturi tube in which is located a fuel nozzle for spraying fuel into the air passing through the intake at high velocity; and have also included an auxiliary air intake for diluting the rich mixture formed in the Venturi tube. In such devices, the Venturi tube is of fixed diameter and form and is usually designed to produce a rich mixture for engine starting and for slow running, the auxiliary air intake being relied upon to furnish the desired quantity and quality of mixture for high speed. Certain carbureters heretofore known have made use of a second or auxiliary fuel nozzle for supplying additional fuel when the auxiliary air intake is in operation. Certain other carbureters have made use of a relatively large intake or Venturi tube capable of supplying air enough for high speeds and provided with an internal choke device adjustable to supply air enough for low speeds only. While such devices furnish a proper mixture for low and for high speeds, they do not furnish a proper mixture for the wide range of speeds lying between those extremes. When a carbureter designed as indicated above, is used in connection with an engine driving an automobile, it is operating at low efficiency most of the time; for the most of the time the engine is running at speeds between low and high, in which case the carbureter cannot be properly adjusted. Various attempts have been made to correct this serious defect by hand-controlled devices for admitting more air, or more fuel, or both, as changing conditions require; but none of these carbureters are efficient or otherwise satisfactory under all speeds.

The present invention has for its main object the production of a carbureter which

will automatically adjust itself to the requirements of the full range of engine speeds in infinitesimal variations.

An air intake or Venturi tube to be most efficient at any given speed, should be circular in form, the fuel nozzle standing concentrically in the center of the circle to interfere as little as possible with the flow of air past it and to evenly distribute the fuel in the moving stream of air. Where the Venturi tube is of fixed diameter, such a device is most efficient at one speed only.

It is one of the objects of this invention to produce an air intake or Venturi tube forming a passage which will retain its efficient form but which can nevertheless be adjusted to vary the amplitude of said passage. And another object of the invention is the production of a device effecting this result automatically.

Still another object of the invention is the production of a device in which the desired result is effected by the action of the engine itself, so that the action of the carbureter will automatically correspond with the action of the engine, supplying more air and fuel when the engine requires it and supplying less air and fuel when the engine requires that, and automatically varying the proportion of air to fuel in accordance with variations in the requirements of the engine under varying conditions.

Still another object of the invention is the production of a device in which the fuel is sprayed into the stream of air at the most efficient point and in the most efficient way at all speeds, the quantity of fuel as well as the quantity of air being automatically regulated by the engine itself.

Still another object of the invention is the production of a fuel nozzle constructed to cause the fuel to be brought in contact with the stream of air in the air intake while said fuel is in the form of an exceedingly thin film, so that the maximum possible surface of the fuel is exposed to the action of the air.

Still another object of the invention is the production of a nozzle of the general character just mentioned, in which the fuel is formed into an exceedingly thin hollow stream, both the interior and exterior of this stream being exposed to the action of air.

Still another object of the invention is the

production of a device in which the atomizing effect of a stream of air flowing at a higher velocity than that of the air in the intake is utilized for the purpose of more quickly securing, and in fact, insuring, an intimate mixture of the fuel and air which will retain its homogeneous character as it passes to the engine.

A further object of the invention is the production of a carbureter having fewer parts, none requiring adjustment; a carbureter which is more efficient and durable than those heretofore known and which is less expensive.

With these and other objects not specifically mentioned in view, the invention consists in certain parts, constructions and combinations which will be hereinafter fully described and then specifically set forth in the 20 claims hereunto appended.

In the accompanying drawings, which form a part of this specification and in which like characters of reference indicate the same or like parts, Figure 1 is a plan 25 view of a device constructed in accordance with the invention, partly broken away; Fig. 2 is an end view of the structure shown in Fig. 1; Fig. 3 is a longitudinal sectional elevation taken on the line 3—3 in Fig. 1; Fig. 4 is a cross-sectional view taken on the line 4—4 in Fig. 1, but illustrating an air inlet differing in form from that shown in Fig. 3; Fig. 5 is a cross-sectional view taken on the line 5—5 in Fig. 3; Fig. 6 is a detail 30 view showing the throttle operating mechanism in elevation; Fig. 7 is a fragmentary detail view illustrating a form of nozzle differing from that shown in Fig. 3; and Fig. 40 35 Fig. 8 is a detail sectional view illustrating a modified form of inlet holding bolt and air nozzle adapted for use when air under pressure is to be used.

In carrying the invention into effect, there is provided a source of air supply, a source 45 of fuel supply, and co-acting means for producing infinitesimal variations in supply of air and supply of fuel in accordance with infinitesimal variations either in the speed of an engine in connection with which the device is used, or in the suction established by that engine. In the best constructions, there is provided an air intake shaped and adapted to retain its form but to vary its 50 55 amplitude in accordance with the varying requirements of the engine in connection with which it is to be used. In the best constructions also, this air intake is circular in form and arranged concentrically with respect to a source of fuel supply or fuel nozzle, the concentric arrangement being maintained throughout the whole range of action of the air intake. In the best constructions also, means are provided for causing the air intake to resume its normal amplitude whenever the requirements of the en-

gine with which the device is used permit it. In the best constructions also, the variable air intake co-operates with the fuel nozzle in the most efficient way, and a throttle or similar means is provided for controlling the flow of air through said intake. In the best constructions also there is provided means for forming fuel into a hollow stream having exceedingly thin walls, both its interior and exterior being exposed to the action of air. In the best constructions also, means are provided for conducting a stream of air to the delivery end of the fuel nozzle where it co-operates with the fuel issuing from the fuel nozzle, the current of air flowing at a higher velocity than the velocity of the air in the intake, so that the fuel is thoroughly atomized and caused to form with the air in the intake a homogeneous mixture.

Many changes and variations may be made in the construction by means of which the invention is carried into effect. Moreover, certain parts of the invention are capable of use independent of other parts, and such independent use is contemplated. The invention is therefore not to be restricted to the details of the specific structure shown and described.

In the device selected to illustrate the invention, 1 indicates a casting having a flange 2 adapted to be bolted to the intake manifold of an engine, or to the engine casting itself where a manifold is not used. Co-operating with this casting 1 is an air inlet 3 having an open mouth 4 in which a hot air pipe, not shown, may be inserted. A clamp screw 5 of a well known character is provided, the function of this clamp screw being to hold a suitable hot air pipe in position within the open mouth 4 of the inlet 3. By an inspection of Fig. 3, it will be seen that this inlet may be swung around to the position which happens to be the most desirable for any particular installation. A modified form of air inlet is shown in Fig. 4 and is marked 6. This modified form of air inlet has an upturning open mouth 7 provided with the usual clamp screw 8. The means for holding this air inlet in position will be hereinafter described. Through the flange 2 is cored or bored a fixed tube 9 through which air flows from the inlet 3 through the flange to the manifold or engine, not shown.

Between the inlet 3 and the fixed tube 9, the casting 1 is chambered at 10 and 11 to receive a pair of co-acting movable members, the function of which is to variably resist the passage of air from the inlet 3 to the fixed tube 9. These movable members are rocking members marked 12 and 13 and may be termed "intake amplifiers" since their main function is to amplify the passage between the inlet 3 and the fixed tube 130

9. Each amplifier is rotatably mounted upon one of a pair of studs 14. Each of these studs has its ends reduced, the reduced ends passing through plates 15, which plates are rabbeted into the casting 1, as clearly shown in Figs. 1, 3, 4 and 5. These plates form the side walls of the chambers within which the amplifiers lie. The reduced ends of the studs 14 project beyond the plates 15, and upon the ends so projecting are threaded nuts 16 which serve to hold the plates 15 in position on the casting 1, and which also serve to hold the studs 14 in position. The amplifier 12 is provided with gear teeth 17 which are intermeshed with gear teeth 18 formed on the amplifier 13. The main purpose of these intermeshed gear teeth is to cause the amplifiers 12 and 13 to move in synchronism. These gear teeth, however, perform another function which will be hereinafter described. The amplifier 12 is provided with a circumferential progressively expanding groove 19 semi-circular in cross section sunk below the gear teeth 17. Similarly, the amplifier 13 is provided with a circumferential progressively expanding groove 20 semi-circular in cross section sunk below the gear teeth 18. These grooves co-act to form a passage circular in cross section, lying in the path of a stream of air passing from the inlet 3 to the fixed tube 9; and as the amplifiers 12 and 13 rock, this circular passage retains its cross-sectional form but is increased in amplitude, this action being due to the progressively expanding character of the grooves 19 and 20.

Located in the passage and concentric therewith is a source of fuel supply or fuel nozzle 21 of well known construction. This nozzle 21 is in open communication with the fuel reservoir 22 formed in the main casting 1. The delivery end of the fuel nozzle 21 lies at the point of least diameter in the air passage and consequently at the point of highest air velocity, a point substantially immovable during the movement of the amplifiers because the centers of the arcs coincident with the bases of the semi-circular grooves 19 and 20 are in a plane including the delivery end of the nozzle. The highest possible efficiency of the fuel nozzle is thus insured irrespective of the position of the amplifiers. Within the fuel reservoir 22 is mounted a float 23 carried on a stem 24, which at its lower end is provided with a ball valve 25 operating to control the flow of fuel into the fuel reservoir. The ball valve 25 operates within a filtering screen 26 which is held in position by means of a plug 27. This plug also serves to hold in position a connection 28 provided with an annular fuel chamber 29 and with a threaded aperture 30 into which a fuel pipe 31 may be screwed. By an inspection of Fig.

3, it will be readily seen that this connection 28 may be swung around to any convenient position. The top of the reservoir 22 is closed by a cover 31 provided with an air vent 32 and with an aperture 33, which serves as a guide for the upper end of the stem 24 before referred to. A cap 34 is provided for inclosing the upper end of the stem 24 and the aperture 33. The cover 31 is held in place by the free end of a spring 35, the opposite end of the spring being secured to the top of the casting 1 by means of a screw 36. A drain plug 37 of well known construction is provided and screwed into the lowermost part of the wall of the fuel reservoir 22. Open communication between the fuel reservoir 22 and the nozzle 21 is established by a hole 38 drilled into the casting 1 from the reservoir to a chamber 39 formed in a boss 40 lying below and between the amplifiers 12 and 13. The lower end of this chamber is closed by means of a plug 41 and into this plug is threaded a cap screw 42 which holds the inlet 3 in position as adjusted.

Within the fixed tube 9 is located a butterfly throttle valve 43 secured to a valve stem 44 journaled in and projecting through the walls of the tube 9. On the projecting end of the valve stem 44 is clamped in a well known manner a stop device 45 having separated horns 46. Each horn is provided with an adjusting screw 47 and retaining spring 48. These adjusting screws are adapted for contact with abutments 49 projecting from the main casting 1 before referred to. It will be noted that these abutments exist on both sides of the device. This is for the purpose of permitting the reversal of the throttle and stop when this is desired; that is to say, the throttle may be mounted in the casting with the stop device upon either side thereof. Beyond the stop device 45 a throttle operating lever 50 is clamped in a well known manner upon the valve stem 44. This lever is so constructed that a hole may be drilled therein at any desired radius within its limits from the axis of the valve stem 44 for establishing connection with any suitable valve operating mechanism leading from any desired direction.

The movement of the amplifiers 12 and 13 is limited by means of a pair of rods 51, the ends of which are pocketed in suitable apertures formed in the plates 15, as clearly shown in Figs. 1 and 3. By an inspection of Fig. 3, it will be readily understood that the amplifiers 12 and 13 are weighted in such manner that their centers of gravity lie below and nearer together than the studs 14 upon which they are mounted, so that in the absence of any disturbing force, gravity will bring them into and hold them at the position shown in Fig. 3, which is the position they occupy when the device is not in action.

In the form of nozzle illustrated in Fig. 7, the upper end of the nozzle 52 is provided with an aperture 53 nearly as large as the main bore of the nozzle. Within the nozzle 52 is located a second nozzle 54, the walls of which are concentric with the walls of the fuel nozzle 52. The nozzle 54 is provided near its upper end with a flange 55, through which one or more channels 56 are cut. The exterior of the upper end of the nozzle 54 is but slightly less than the aperture 53 of the fuel nozzle. The nozzle 54 is hollow and adapted to conduct a stream of air to the delivery end of the fuel nozzle. When this stream of air is to be induced by the suction of the engine itself, the nozzle and allied parts will be in the form shown in Fig. 7. By an inspection of Fig. 7, it will be seen that this air nozzle 54 is formed integrally with the plug 57 screwed into the boss 40 before referred to, and it will be further seen that screwed into this plug 57 is a clamping cap screw 58 having a longitudinal hole 59 and a lateral hole 60 drilled therein for the purpose of conducting air from the interior of the inlet 3 to the interior of the nozzle 54. It will be readily understood also that the clamping cap screw 58 also performs the function of holding the air inlet 3 in adjusted position. It will be understood that by the structure just described, the fuel is formed into a hollow stream, the quantity issuing from the nozzle being controlled by the channel or channels 56 in the flange 55; and it will be further understood that the fuel issues from the fuel nozzle in the form of an exceedingly thin tubular film of exceedingly large surface area, and that both the interior and exterior of this thin film is brought into contact with the air passing through the air nozzle 54 and the air passing through the passage between the amplifiers 12 and 13.

When air under pressure is to be used within the hollow stream of fuel so that the velocity of the air within the stream of fuel will exceed the velocity of the air through the intake passage, neither the cap screw 42 nor the cap screw 58 will be used, but in place thereof a different form of clamping screw marked 61, and shown in Fig. 8, will be substituted. This clamping screw has a longitudinal hole 62 drilled throughout its length and beyond its clamping surface is provided a threaded aperture 63 adapted for use in connection with a suitable pipe for conducting air under pressure from any suitable source of the same. When this device is used, there may be provided a check valve consisting of a ball 64 normally closing the upper end of the aperture 63. The upper end of the hole 62 is enlarged at 65 to accommodate the ball 64 and the upward movement of the ball 64 is limited by means of a pin 66. The enlarged portion 65 of the hole

62 is in open communication with the bore 67 of an air nozzle 68 adapted to take the place of the air nozzle illustrated in Fig. 7. The air nozzle 68 is provided with a flange 69 having one or more channels 70 cut therethrough for the same purpose as the flange 55 and channels 56 in the air nozzle 54 shown in Fig. 7; that is to say, to centralize the air nozzle within the fuel nozzle to form a thin film of fuel and to control the flow of said fuel. In the event of an overflow of fuel into the air nozzle 68 when the device is not in use, this ball check valve 64 will prevent flooding of the clamping cap screw 61 and the pipe connected therewith. The check valve is not necessary however, except for the purpose just described, and in many installations might be omitted with safety.

The operation of the device illustrated in Figs. 1 to 6 inclusive is as follows, it being understood that the parts are in normal position, or that shown in Fig. 3, in which the passage between the members is smallest. It may be here remarked that the relative areas of the intake in normal position and of the fuel nozzle are designed for highest possible efficiency under the most unfavorable conditions; that is to say, in starting the engine in cold weather or in high altitudes. The throttle being open slightly to start the engine in connection with which the device is used and the engine being turned over either by hand or by mechanical means, a partial vacuum is established in the fixed tube 9. Air under atmospheric pressure can only reach this fixed tube by coming through the inlet 3 and through the small passage formed between the amplifiers 12 and 13 around and concentric with the fuel nozzle. The weight of these members is sufficient, under the low suction established at this time, to prevent them from moving; or, at least, to permit only a very slight movement, the exact position depending entirely upon the speed of cranking of the engine. In either event, a relatively small amount of air is drawn between the amplifiers as compared with the amount of fuel drawn from the fuel nozzle. The result is a very rich mixture, which is precisely what is desired at this time. As the engine picks up its cycle of operations, operates under its own power and increases its speed, the throttle still being opened only a little, the suction increases and the amplifiers 12 and 13 rock a little more so that more air is admitted, the only resistance to this movement being the weights of the amplifiers themselves. It may be here remarked that the incoming air acting upon the gear teeth 17 and 18 of the amplifiers 12 and 13 tends to aid this opening movement against the resistance of the weights of the amplifiers. The suction being stronger at this time, more fuel is also drawn from the

nozzle 21, so that the volume of both air and fuel is increased, while the proportion of air to fuel is slightly decreased, both of which are precisely what is needed at this time. 5 Then if the throttle is opened still more, the suction at once increases in the fixed tube 9 and this results in opening the passage between the amplifiers 12 and 13 still more and drawing still more fuel from the nozzle 21; but since the fuel drawn in is heavier than the air drawn in, the proportion of air to fuel increases. The effective result is a greater quantity of mixture not so rich as when starting but still rich enough for a 15 quick pick-up, or increased speed of the engine. This is precisely what is needed at this time. All through the wide range of engine speeds and infinitesimal variations therein, the mixture grows thinner as speed 20 increases until at maximum speed it is thin-nest. This is precisely what is desired at this time. Any possible tendency of the device to produce a mixture too thin at high speeds is prevented as follows: As the ampli- 25 fiers move from their normal position to wide open position, their centers of gravity move from positions almost under the studs 14 to positions nearer together. The rotat- 30 ing effect of the weights upon the amplifiers in normal position is very little because they are then very nearly under the supporting studs of the amplifiers; but as they are swung up toward each other by the move- 35 ment of the amplifiers, their turning effort is increased and this increased turning effort operates against the action of the in- flowing stream of air and thereby tends to resist the rocking movement of the amplifiers. When the engine is running at full 40 speed with the throttle wide open, this turn- ing effort due to gravity is greatest and the effective result is to restrict the passage for and maintain the velocity of the stream of 45 air between the amplifiers as the flow of fuel through the nozzle is retarded. The proper mixture is thus insured. In the event of a heavy load being placed upon the engine while running at high speed, as 50 for instance when the engine is driving an automobile and the latter is climbing a hill, the speed of the engine reduces, and the suc- 55 tion is also reduced. This results in a move- ment of the amplifiers back toward normal position in strict accordance with the variations in the suction. This further restric- 60 tion of the passage results of course in a richer mixture, which is precisely what is needed at this time. If the engine is slowed down by a partial closure of the throttle, 65 the amplifiers automatically assume the proper position for the resulting suction and if the throttle is entirely closed and suc- tion ceases, the amplifiers will automatically return to their normal position or that shown in Fig. 3. Throughout the whole

range of possible speeds, the amplifiers ad- 70 just themselves to the proper position for that speed, or rather are adjusted by the engine itself, infinitesimal variations in the supply of air and the supply of fuel and infinitesimal variations in the proportion of air to fuel resulting in accordance with 75 infinitesimal variations either in the speed of the engine or in the suction established by the engine.

The operation of the device, when the nozzle illustrated in Fig. 7 is used, is the same as the operation above described except in that the fuel is first formed into a hollow stream having exceedingly thin 80 walls, and that both the interior and exterior of these thin walls are exposed to the action of air, the result being a quicker and more thorough mixture of the fuel and air than is possible with any nozzle from which 85 the fuel issues in globular or otherwise solid form. This is due to the fact that the largest possible surface of the fuel is exposed to the direct action of the air.

The operation of the device in which the structure shown in Fig. 8 is substituted for the fuel nozzle shown in Fig. 7, is the same as the operations above described except that since the air within the thin tubular film of fuel is conducted under pressure to the de- 90 liveries end of the fuel nozzle, and at a ve- 95 locity higher than the velocity of the air induced in the intake by the suction of the engine in connection with which the carburetor is used, the inner stream of air will immedi- 100 ately expand as soon as it issues from the air nozzle and literally blow the thin film of fuel to atoms, and in so doing will force these atoms radially outward into the in- 105 coming stream of air in the intake, thus insuring a practically instantaneous conver- 110 sion of the air and fuel into a homogeneous mixture.

It will thus be seen that the device is ab- 110 solutely automatic in action, adjusting it- 115 self—or rather being adjusted by the engine—infinitesimally to meet the variable re- 120 quirements of the engine in connection with which it is used; that there are no delicate parts to get out of order or out of adjustment, 125 no adjustments being necessary; that it con- 130 tains fewer parts than carburetors hereto- 135 fore known, and consequently is extremely simple and inexpensive in design, and more durable and more efficient in action.

What is claimed is:

1. In a carburetor, an air intake having co-acting rocking members provided with co-operating circumferential progressively expanding grooves semi-circular in cross section said members being operative by suc- 125 tion established therebetween and acting thereupon to vary the amplitude of the pas- 130 sage between the members in accordance with suction variations.

2. In a carbureter, an air intake having intergeared co-acting rocking members provided with coöperating circumferential progressively expanding grooves semi-circular 5 in cross section said members being operative by suction established therebetween and acting thereupon to vary the amplitude of the passage between the members in accordance with suction variations.
- 10 3. In a carbureter, an air intake having co-acting rocking members provided with intermeshing geared teeth upon their peripheries and with coöperating circumferential progressively expanding grooves semi-circular 15 in cross section and sunk in said geared teeth said members being operative by suction established therebetween and acting thereupon to vary the amplitude of the passage 20 between the members in accordance with suction variations.
4. In a carbureter, the combination with an air intake having co-acting rocking members provided with coöperating circumferential progressively expanding grooves semi-circular 25 in cross section said members being operative by suction established therebetween and acting thereupon to vary the amplitude of the passage between the members in accordance with suction variations, of a 30 source of fuel supply located between said members.
5. In a carbureter, the combination with an air intake having co-acting rocking members provided with coöperating circumferential 35 progressively expanding grooves semi-circular in cross section said members being operative by suction established therebetween and acting thereupon to vary the amplitude of the passage between the members 40 in accordance with suction variations, of a fuel nozzle located between said members and concentric with the grooves thereof.
6. In a carbureter, the combination with an air intake having co-acting rocking members provided with coöperating circumferential 45 progressively expanding grooves semi-circular in cross section and adapted to maintain a substantially constant point of highest air velocity in the passage between the members as the members move 50 said members being operative by suction established therebetween and acting thereupon to vary the amplitude of the passage between the members in accordance with suction variations, of a fuel nozzle the delivery 55 end of which is located within said passage at said point of highest air velocity.
7. In a carbureter, an air intake having co-acting rocking members provided with coöperating circumferential progressively 60 expanding grooves semi-circular in cross section said members being operative in one direction by suction established therebetween and acting thereupon to increase the amplitude of the passage between the members in accordance with suction increase said members having counter-weighted portions positioned and operative to partially counteract the effect of the suction upon the members as they approach wide open position 65 and to return said members to normal position when suction ceases.
- In testimony whereof, I have signed my name to this specification in the presence of two subscribing witnesses.
